UNITED STATES PATENT OFFICE.

EUGENE RILEY, OF WOODRIVER, ILLINOIS.

FOOT-REST.

1,221,596.

Specification of Letters Patent.

Patented Apr. 3, 1917.

Application filed April 22, 1916. Serial No. 92,898.

To all whom it may concern:

Be it known that I, EUGENE RILEY, a citizen of the United States, residing at Wood-river, in the county of Madison and State of Illinois, have invented new and useful Improvements in Foot-Rests, of which the following is a specification.

This invention contemplates the provision of a foot rest designed for use in connection with a radiator, and aims to provide a construction wherein the foot rest can be supported in any desired location about the radiator, and when associated therewith subsequently adjusted to assume different inclined positions to the comfort of the user.

Another important object of the invention resides in the provision of means for supporting the foot rest proper, which when the foot rest is folded against the radiator in an inactive position, will be wholly disposed from view between the sections of the radiator, thereby adding to the appearance of the latter, as well as eliminating projections or protuberances to catch in the clothing.

A further characteristic of the invention resides in the provision of a supporting means for the foot rest proper, which is capable of lateral adjustment with respect thereto, to permit the device as a whole to accommodate itself to radiators of different widths.

The invention further embodies the desired features of simplicity in construction, durability, and is easily manipulated for the purpose intended.

Other objects and advantages will appear as the following description is read in connection with the accompanying drawings, the invention residing in the construction, combination and arrangement of parts as claimed.

In the drawings forming part of this specification like numerals of reference indicate similar parts in the several views and wherein:

Figure 1 is a front elevation of the foot rest showing the same folded against the radiator.

Fig. 2 is a vertical sectional view through the radiator showing the foot rest in a position for use.

Fig. 3 is a bottom plan view of the foot rest showing the manner of attaching the supporting means thereto.

Fig. 4 is an enlarged side elevation of the device as a whole removed from the radiator.

Fig. 5 is a detail view of one of the brackets.

Before entering into a detail description of what is herein shown I desire to have it understood that the same is merely illustrative of one embodiment of the invention to which I do not limit myself, and that such changes in the construction and arrangement of parts may be resorted to when desired as fall within the scope of what is claimed.

As shown in this particular instance use is made of a pair of rods indicated at 10, which are adapted to pass between adjacent sections of the radiator A at remote points. Any suitable means may be employed for holding the rods fixed relatively to the radiator in a horizontal position, but each of the rods is preferably provided with a cross piece 11 constituting a head adapted to bridge the adjacent sections of the radiator at the front thereof, while slidably mounted upon the opposite end of each rod is a similar cross piece 12 adapted to be held in effective engagement with the radiator at the opposite side thereof through the instrumentality of the thumb nut 13 adjustably mounted upon the threaded extremity of said rods. The rods 10 have their forward ends forked as at 14, and pivotally receive lugs projecting from the under surface of the foot rest proper, indicated at 15, which latter is obviously mounted for vertical swinging movement.

One of the lugs as hereinabove mentioned projecting from the under side of the foot rest proper and pivotally connected with one of the rods 10 is fixed upon the foot rest and indicated at 16, while the other lug adapted for association with the other of said rods is indicated at 17 and forms part of a bracket plate 18 which is disposed at right angles to its associated lug 17 as clearly shown in Fig. 5. The bracket 18 is provided with a longitudinally disposed slot 19, and projecting through said slot from the foot rest is a threaded pin 20 having associated therewith a thumb nut 21, which parts hold the bracket 18 connected with the foot rest. However by reason of this construction the bracket 18 together with its associated rod 10 can be adjusted toward or away from the other of the said

rods 10 to permit the foot rest as a whole to accommodate itself to radiators of different widths, or in other words to radiators comprising a different number of sections. 5 This fact coupled with the fact that the rods 10 are capable of adjustment vertically between the adjacent sections of the radiator, allows the foot rest to be located in any convenient position about the radiator as de- 10 sired.

With a view of holding the foot rest 15 in any of its different angular positions, I preferably employ the arcuate shaped arms 22, which are pivotally connected at one end 15 to lugs projecting from the under side of the foot rest, while each of the said arms is provided with a longitudinally disposed slot 23 through which projects a pin 24 carried by each of the rods 10 at a point ap- 20 proximately midway of their length. The upper wall of the slot is provided with a longitudinally disposed series of notches 25 adapted to interchangeably engage the pin 24, whereby the foot rest 15 under its own 25 weight can be supported in different inclined positions to the comfort of the user. One of the arcuate shaped arms 22 is pivotally connected to a fixed lug 26 projecting from the under side of the foot rest, while 30 the other of said arms is pivotally connected to a lug 27 forming a part of a bracket plate 28 adjustably secured to the under side of the foot rest as clearly shown in Fig. 3. The bracket plate 28 is constructed similarly 35 to the bracket plate 18, being provided with a longitudinally disposed slot 29 for the reception of a threaded pin 30 projecting from the foot rest and having associated therewith a thumb nut 31 for holding the bracket 40 connected with the foot rest. The bracket 28 is disposed beneath the bracket 18, adjacent the same side of the foot rest 15, so that the associated arcuate shaped arm 22 can be simultaneously adjusted with its as- 45 sociated rod 10 laterally of the foot rest 15, for the purpose hereinabove mentioned for permitting the device as a whole to accom- 50 modate itself to radiators of different widths. 55 The device is not only simple in its construction, which provides for a quick adjustment of the foot rest proper, but it will be particularly noted that the means em- 55 ployed for holding the foot rest in its dif- 60 ferent adjusted positions, including the pin 24 and arcuate shaped arm 22, are wholly disposed from view between the sections of the radiator, when the foot rest 15 is in the position shown in Fig. 1. This arrange- 65 ment eliminates all projections or extensions from the radiator which would not only catch in the clothing, but would present an unsightly appearance. By merely removing the cross piece 12 and thumb nut 13, the 65 device in its entirety can be easily associ-

ated with or removed from the radiator as the occasion may require.

While it is believed that from the foregoing description the nature and advantages of the invention will be readily apparent, 70 I desire to have it understood that the component parts of the invention may be constructed from suitable material, and vary in design and proportions without departing from the spirit of the invention. 75

What is claimed is:—

1. A device of the class described comprising rods passed horizontally between the sections of a radiator, means for holding each of said rods fixed relatively thereto, 80 foot rest pivotally mounted upon the forward ends of said rods, a lug projecting laterally from each rod, and notched arms pivotally connected to said rest and adapted to engage said lugs to hold the foot rest in 85 different inclined positions.

2. A device of the class described comprising rods passed horizontally between the sections of a radiator, means for holding each of said rods fixed relatively thereto, a 90 foot rest pivotally mounted upon the forward ends of said rods, a lug projecting laterally from each rod, and arcuate shaped arms pivotally connected to said rest, each of said arms having a longitudinal slot re- 95 ceiving said lugs and notches for engagement therewith to hold the foot rest in different inclined positions with respect to the radiator.

3. A device of the class described comprising rods horizontally disposed between the sections of a radiator, a cross piece carried by each rod for engagement with the front of the radiator, a similar cross piece adjustably mounted on the opposite end of 105 the rods for engagement with the opposite side of the radiator, a nut adjustably mounted on the rod for holding the last mentioned cross pieces in adjusted position, a foot rest pivot- 110 ally mounted upon the forward ends of said rods, a lug projecting laterally from each rod, and notched arms pivotally connected to said foot rest and adapted to engage said lugs to hold the rest in different inclined 115 positions.

4. A device of the class described comprising a foot rest, supporting rods pivoted at one end to said foot rest, one of said rods together with its pivot being adjustable laterally toward and away from the other of said rods, means for holding said parts in adjusted position, said rods adapted to be passed horizontally between the sections of the radiator, means for holding the said rods fixed relatively thereto, a lug pro- 120 jecting from each rod, and notched arms pivotally connected to the foot rest and adapted to engage said lugs to hold the rest in different inclined positions. 125

5. A device of the class described compris- 130

ing a foot rest, supporting rods pivotally connected at one end to said foot rest and adapted to be passed horizontally between the sections of the radiator, a lug projecting laterally from each of said rods, notched arms pivotally connected to said rest and adapted to engage said lugs to hold the foot rest in adjusted position, one of said rods and its associated arm being connected to the foot rest for adjustment toward and away from the other of said

corresponding parts, means for holding the adjustable rod and arm in a fixed position, and means for holding the rods fixed relatively to the radiator.

15 In testimony whereof I affix my signature in presence of two witnesses.

EUGENE RILEY.
